UNITED STATES PATENT OFFICE.

GEORG IHSSEN, OF HANOVER, GERMANY.

CUPOLA AND BLAST FURNACE.

SPECIFICATION forming part of Letters Patent No. 415,206, dated November 19, 1889.

Application filed June 23, 1888. Serial No. 278,066. (No model.)

To all whom it may concern:

Be it known that I, GEORG IHSSEN, a subject of the Emperor of Germany, and residing at Hanover, in Germany, have invented a new and useful Improvement in Cupola and Blast Furnaces, of which the following is a specification.

This invention relates to cupola and blast furnaces; and it consists in improvements therein, as hereinafter set forth, and specifically pointed out in the claims.

The improvement relates to the crucible, or that part of the furnace extending from the sole to a distance above the tuyeres.

15 A further improvement relates to the position, construction, and relative arrangement of the tuyeres.

Reference being made to the accompanying drawings, which illustrate a cupola and blast furnace constructed according to the improvement, Figure 1 is a vertical section thereof on line A B, Fig. 4. Fig. 2 is a side elevation. Fig. 3 is a vertical section on line C D, Fig. 6. Figs. 4 and 5 are respectively horizontal sections on lines E F G H, Fig. 1. Fig. 6 is a section on line J K, Fig. 3.

The same letters of reference indicate the same parts throughout the figures.

In the improved furnace the shaft *b* and boshes *c* are constructed as formerly, each circular in horizontal cross-section, but that part of the crucible *d* which extends downward from the boshes to the level of the tuyeres is elliptical in horizontal cross-section, with vertical sides. Below the level of the tuyeres the remainder of the crucible, except where outlets or chambers are formed in the sides, is of cylindrical shape down to the sole, the diameter of the cylindrical part being equal to the major axis of the elliptical part of the crucible *d*. Since the lower part of the crucible is cylindrical and the upper part elliptical, there will be formed at the line of junction two abrupt crescent-shaped set-backs, one on each side below the lower edge of the elliptical portion of the crucible, these set-backs completing the difference between the smaller axis of the ellipse of the upper part and the diameter of the circle of the lower part of the crucible. The tuyeres *a a'* are situated at or in these set-backs. I prefer to make one of the set-backs at a higher level than the other—

that is to say, by continuing the elliptical portion of the crucible to a lower level on the one side than on the other. In the walls of the furnace above the set-backs are formed the chambers *e e'*, or air-chests, supplied with a blast of air in the usual manner and communicating, respectively, with the interior of the furnace through slits *a a'*, which form the tuyeres in or under the set-backs aforesaid, said slits *a a'* being also crescent-shaped, the one edge corresponding with the cylindrical wall of the crucible, the other lying parallel with the lower edge of the elliptical portion thereof. The slits *a a'* are inclined in order to throw the blast downward into the lower part of the crucible.

By drawing the sides of the furnace into an elliptical form in the region of the melting-zone—that is to say, toward the level of the tuyeres—and so flattening the charge an equal temperature is obtained over all the melting-zone, and the air-blast acts more equally to the center of the charge, this being more especially important in the larger furnaces with small pressure of air-blast, in which formerly the central portions of the charge were not touched by the blast. For the same reason the improvement also tends to the complete utilizing of all the coke. The position and shape of the tuyeres assist in like manner by spreading the air-blast over all in a manner substantially proportional to thickness of the charge. Furthermore, the iron, by its weight falling vertically downward in the crucible, tends to spread out the coke toward the side, and so heap up the same under the set-backs—that is to say, under the direct action of the tuyeres. The melted iron, therefore, is not disturbed by the blast, and decarburization of the iron does not take place. The position of the tuyeres prevents them from becoming choked.

I claim as my invention—

1. In cupola and blast furnaces, the combination of a shaft provided with boshes of circular horizontal cross-section with a crucible of elliptical horizontal cross-section below said boshes.

2. The combination of a shaft provided with boshes of circular horizontal cross-section with a crucible of elliptical horizontal section below said boshes and extended be-

low to a cylindrical shape below said elliptical portion.

3. A shaft provided with a crucible composed of an upper part of elliptical horizontal cross-section and a lower part of cylindrical shape, the major axis of the ellipse being equal to the diameter of the cylinder.

4. A shaft provided with a crucible composed of an upper part of elliptical horizontal cross-section and a lower part of cylindrical shape, so as to form set-backs below said upper part, in the manner set forth, in combination with tuyeres in said set-backs.

5. A shaft provided with a crucible com-

posed of an upper part of elliptical cross-section and a lower part of cylindrical shape connected so as to form two set-backs, one on each side below said upper part, one set-back at a higher level than the other set-back, in combination with tuyeres in said set-backs. 15 20

In testimony whereof I have signed this specification in the presence of two subscribing witnesses.

GEORG IHSSEN.
